United States Patent Office.

ARCHIBALD KELLY, OF SHARPSBURG, PENNSYLVANIA.

Letters Patent No. 92,195, dated July 6, 1869; antedated June 19, 1869.

SHREDDING-AUGER FOR BARRELS.

The Schedule referred to in these Letters Patent and making part of the same.

To all whom it may concern:

Be it known that I, ARCHIBALD KELLY, of Sharpsburg, in the county of Allegheny, and State of Pennsylvania, have invented a new and useful Improvement in Shredding-Auger for Barrels; and I do hereby declare that the following is a full, clear, and exact description thereof, reference being had to the accompanying drawings, and to the letters of reference marked thereon.

In boring bung-holes in barrels, the edge inside of the barrel is left rough and ragged by the auger, or other instrument used for making the bung-hole, and the inner surface of the staves of barrels are rough and uneven.

This rough and ragged condition of the lower edge of the bung-hole, and the uneven and rough surface of the inner side of staves, are impediments, obstacles, and obstructions, which prevent the proper cementing or coating of the inside-surface of barrels used for holding hydrocarbon-oils, for the cement or coating-material gathers, coagulates, and adheres to the rough and ragged edge and surface around the bung-hole of the barrel, and, in "driving" the bung, the cement or coating around the bung-hole is knocked off into the oil in the barrel, thereby injuring the oil, and also causing a leakage around the bung.

The nature of my invention consists in providing a shredding-auger for making the inner edge and surface around the bung-hole of barrels smooth and even, said auger being constructed, arranged, and operating in the manner hereinafter described.

To enable others skilled in the art to make and use my invention, I will proceed to describe its construction and operation.

In the accompanying drawings, which form part of my specification—

Figure 1 is a side elevation of my improvement in shredding-auger.

Figure 2 is a vertical section of the same.

Figure 3 is a transverse section of its cutting-head.

In the drawings—

A represents the shank of the auger, on the upper end of which is secured a handle, D.

The shank A is placed in a metal sleeve, C, and is held in the sleeve by means of a projecting pin, o, which moves in the slot X.

To the lower end of the sleeve C is pivoted, at g, a cutter-head, B, provided with a knife, f, which may be secured in the cutting-head by means of wedges or a set-screw.

Around the sleeve C is placed a spiral-spring, e, to

the lower end of which may be attached a flange, as indicated by the dotted lines marked S.

The upper end of the sleeve C is provided with a narrow flange, for the purpose of holding the spring on the sleeve, and also for making the spring operative in holding the cutter-head to its work.

As the construction of my improvement, and the arrangement of the several parts, and the relation that they bear to each other, will readily be seen and understood from the foregoing description, and by reference to the accompanying drawings, I will therefore proceed to describe its operation, which is as follows:

The end of the cutting-head B is inserted in the bung-hole of the barrel. I then press down on the handle D, which will force down the shank A, and the lower end of the shank, pressing on the end of the cutting-head B, will throw it into the position represented by the dotted lines y, and the spiral spring will draw the head up against the stave, represented by lines h, in which the bung-hole is made.

I then turn the handle D to the right, which will bring the pin o into the recess i, and cause the sleeve C to revolve with the shank A, and the revolving of the sleeve C will rotate the cutter-head B, which, being held up against the under side of the stave, through the medium of the spiral spring, the knife f will shave off the ragged edge of the bung-hole, and make that part of the stave around the bung-hole smooth and even.

The handle D is then turned back sufficient to bring the pin o opposite to the slot X.

The handle D is then drawn up, which will raise the shank A off the end of the cutter-head B, which will drop down, by its own gravity, into the position represented in fig. 1.

The auger is then withdrawn, and the barrel will then be ready for cementing, which process is well understood.

Barrels prepared in the manner described will allow the surplus cement to flow out, leaving the surface around the bung-hole smooth, even, and perfectly cemented.

Having thus described the nature, construction, and operation of my improvement,

What I claim as of my invention, is—

The shredding-auger herein described, consisting of shank A, cutting-head B, spring e, when all are constructed and arranged to operate as set forth.

Witnesses:
